(57) CLAIM

The ornamental design for a card case, as shown and described.

DESCRIPTION

FIG. 1 is a left, top perspective view of a card case, showing my new design in a partially open state;

FIG. 2 is a right, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the card case in a closed state; and,

FIG. 10 is a perspective view showing a card case in an unfolded state.

The broken lines in the drawings illustrate the portions of the card case, which form no part of the claimed design.

1 Claim, 10 Drawing Sheets
